UNITED STATES PATENT OFFICE.

JAMES B. LEE, OF KNOXVILLE, TENNESSEE.

CORD-CLAMPING DEVICE.

No. 891,484.

Specification of Letters Patent.

Patented June 23, 1908.

Application filed October 10, 1907. Serial No. 396,708.

To all whom it may concern:

Be it known that I, JAMES B. LEE, a citizen of the United States, residing at Knoxville, in the county of Knox and State of Tennessee, have invented a new and useful Improvement, 5 in Cord-Clamping Devices, of which the following is a specification, reference being had to the accompanying drawing.

My improvement relates particularly to 10 devices for securing, without tying, the ends of light or small cords and tapes, such as shoe strings and similar cords or tapes used for lacing.

The improvement is applicable also for the 15 securing of the ends of cords used otherwise than for lacing through such eyelets or hooks as are ordinarily applied to shoes, gaiters, leggings, and similar articles.

The object of the improvement is to produce 20 such a device in a form adapted (1) to easy securing to leather or similar sheet-form material, and (2) to permit the ready drawing of the cord into a firm and effective engagement and the ready withdrawal of said 25 cord from such engagement.

In the accompanying drawings, Figure 1 is a 30 plan of a clamping device embodying my improvement; Fig. 2 is a side elevation of the same device; Fig. 3 is a plan similar to Fig. 1 with an eyelet applied for securing the device to a sheet of leather or cloth; Fig. 4 is a section on the line 4—4 of Fig. 3; Fig. 5 is a perspective view of an uncompressed eyelet such as is shown applied in Figs. 3 and 4; 35 Fig. 6 is a section on the line 6—6 of Fig. 1.

My clamping device is an elongated, one-piece flexible wire structure, one end of which is secured to the leather, cloth, or other sheet-form material, and the other end of which is 40 adapted to yieldingly clamp or pinch the cord at two places.

Referring to said drawings, 1 is an approximately horizontal tongue formed by 45 folding the wire upon itself in a horizontal plane, the closed or outer portion of the tongue being directed away from the end of the device which is secured to the leather or other material. At each side of the tongue, 1, is a jaw, 2, resting in a plane slightly 50 oblique to said tongue, so that the inner end of the tongue normally rests slightly above said jaws. The tongue and the jaws are joined by loops, 3, standing in planes which are approximately upright and parallel to 55 each other and said tongue and jaws.

From the inner end of each jaw, 2, the wire

is formed into an arm, 4, extending around one side of an approximately horizontal circle the center of which is in or near the horizontal axis of the device, the ends of said arms being 60 opposed to each other and preferably meeting. Said arms together constitute an eye by which the device may be secured to the leather or other sheet-form material by means of stitching, 5, as shown in Fig. 1, or 65 by means of an eyelet, 6, extending through the sheet, 7, of leather or similar material and having its lower flange binding against the lower face of the leather and having its upper flange binding over said arms. Where said 70 arms pass away from the eyelet to join the jaws, 2, the upper flange of the eyelet should be cut away to form notches, 8, as shown in Figs. 3 and 5, said notches being of proper form to receive said arms. 75

For the securing of a cord, 9, the cord is drawn sidewise along the upper faces of the inner portions of the jaws, 2, and beneath the inner portion of the tongue, 1, (the adjacent curved portions of the loops, 3, serving to 80 guide the cord downward) and toward the outer end of said tongue and jaw. In this way, the cord is engaged at two places, namely between each side of the tongue and the adjacent jaw, 2, the tongue extending 85 partially between said jaws, as above described, so that the cord is wrapped partially around the wire at each side of the tongue for the making of greater frictional engagement (see Fig. 6). The tongue, 1, the loops, 3, 3, 90 and the jaws, 2, 2, together make a sufficient length of wire to permit sufficient movement of the tongue even when the wire is strong enough to make a strong resistance to flexing.

As shown in the drawings, the tongue, 1, 95 extends forward far enough to prevent the cord from passing over such end when the cord is, at any time, drawn forward as far as the jaws, 2, extend.

For the releasing of the cord, it is forcibly 100 drawn sidewise away from the outer end of the tongue and jaws until it is freed from the clamping or gripping.

I claim as my invention:

1. A one-piece wire clamping device of the 105 nature described comprising a tongue, a jaw at each side of said tongue, loops joining said jaws and said tongue, and arms for securing said device to sheet-form material.

2. A one-piece wire clamping device of the 110 nature described comprising a tongue, a jaw at each side of said tongue, loops joining said

jaws and said tongue, and curved, approximately semi-circular arms extending from said jaws.

3. A one-piece wire clamping device of the nature described comprising a tongue, a jaw at each side of said tongue, loops joining said jaws and said tongue, and arms for securing said device to sheet - form material, said tongue extending beyond the outer ends of 10 said jaws.

4. In a clamping device of the nature described, the combination with a one-piece wire structure comprising a tongue, a jaw at each side of said tongue, loops joining said 15 jaws and said tongue, and curved, approximately semi-circular arms extending from said jaws, of an eyelet engaging said arms.

5. In a clamping device of the nature described, the combination with a one-piece wire structure comprising a tongue, a jaw at 20 each side of said tongue, loops joining said jaws and said tongue, and curved, approximately semi-circular arms extending from said jaws, of an eyelet engaging said arms, said eyelet having notches, 8, in one of its 25 flanges.

In testimony whereof I have signed my name, in presence of two witnesses, this 4th day of October, in the year one thousand nine hundred and seven.

JAMES B. LEE.
